[57] **CLAIM**

The ornamental design for a cutting tool for flexible plastic conduit, as shown and described.

DESCRIPTION

FIG. 1 is a perspective view of a cutting tool for cutting flexible conduit, embodying my new design, with the tool in a partially opened position.

FIG. 2 is an enlarged side elevational view thereof, the opposite side being a mirror image of the side shown.

FIG. 3 is a rear elevational view thereof.

FIG. 4 is a front elevational view thereof.

FIG. 5 is a top plan view thereof.

FIG. 6 is a bottom plan view thereof.

FIG. 7 is an enlarged side elevational view thereof, but with the tool in a closed position, the opposite side being a mirror image of the side shown.

FIG. 1

FIG. 3

FIG. 4

FIG. 2

FIG. 5

FIG. 6

FIG. 7
